UNITED STATES PATENT OFFICE.

JOHN G. MUELLER, OF DAYTON, OHIO.

RAILWAY-RAIL BRACE.

Application filed May 25, 1922. Serial No. 563,515.

To all whom it may concern:

Be it known that I, JOHN G. MUELLER, a citizen of the United States, residing at Dayton, in the county of Montgomery and State of Ohio, have invented certain new and useful Improvements in Railway-Rail Braces, of which the following is a specification, reference being had therein to the accompanying drawing.

10 This invention relates to improvements in railway rail braces.

The object of the invention is to brace the ball of the rail by adjustable brace-members adapted to be applied to rails of different vertical dimensions.

Another object is to combine with such brace-members other members which embrace the web and base of the rail.

In the accompanying drawings;

20 Fig. 1 is a view showing my invention applied to a pair of railway rails;

Fig. 2 is an enlarged side elevation of my brace in its entirety showing a rail in cross section;

25 Fig. 3 is a detail sectional view on the line 3—3 of Fig. 2 showing how two of the brace members interfit;

Fig. 4 is a detail sectional view on the line 4—4 of Fig. 2 likewise showing the 30 interrelation of two of the members.

In the drawings I have illustrated a conventional railway rail comprising a base 1, a web 2 and a tread 3, the latter being formed with the usual "ball" of the rail 4, 35 being the part at the side and on the under surface of the tread.

The numeral 5 designates the tie rod which is used by means of threaded portions 6, nuts 7 and washers 8 to clamp the 40 various members of the brace in their relation to the rail and to each other; and which tie rod will preferably extend from rail to rail, as indicated in Fig. 1, so as to afford the means, with its threaded portions, nuts and washers, of not only clamping the brace-members with relation to themselves and the rail, but also perform the further office of inter-connecting or bracing one rail with respect to the other.

45 Referring again to Fig. 2, it will be seen that my brace comprises outer braces, des-

ignated 9, adapted at their upper inclined ends, 10, to bear against and support the ball of the rail and to preferably contact, as at 11, with the web near its upper edge; 55 and having practically vertical portions 12 bored out at 13 to receive the tie rod 5. The nuts 7 force the washers 8 against these outer braces and cause them to impinge forcibly and solidly against the balls of the 60 rail. The inner faces of the members 9 are grooved, as shown at 14 for a purpose now to appear.

Inner braces 15 intervene between the outer braces 9 and the base and web of the 65 rail and extend downward and form portions 16 below the rail base. These inner braces also bored out, as shown at 17, to receive the tie rod 5.

They are further formed with webs or 70 flanges 18 which enter the grooves 14 in the outer braces with a clearance space 19 within the groove and an additional clearance space 20 between the inner and outer braces to permit of the outer braces being adjust- 75 ed to fit rails of different vertical dimensions. Any adjustment of the outer braces longitudinally of their inclined members will cause them to slightly change their position with reference to the inner braces, 80 and hence these clearance spaces 19 and 20.

It will be noted that not only do the inner braces brace and strengthen the outer braces but that they impinge and forcibly fit 85 against the rail web so as to brace the web from movement and vibration in lateral directions.

Filler blocks 21 are bored at 22 to fit over the tie rod 5 and have webs 23 which enter grooves 24 in the inner braces 15, as shown 90 more clearly in Fig. 4. In this way the filler blocks and inner braces are kept in proper yet movable relation so that when the several members are clamped by the nuts and washers the hook-like shoulders 25 of the 95 filler blocks can be moved up into contact with the edges of the rail base.

Referring again to the outer braces 9 and inner braces 15 it will be observed that they are fashioned to leave a clearance space 27 100 between them so that the outer braces may as before stated, be adjusted with relation

to the inner braces when the outer braces are being fitted against rails of different vertical dimensions. These outer and inner braces contact with each other above and below the spaces 27, as seen at 28 and 29.

It will now be seen that by the simple expedient of adjustment of one or both, usually both, nuts 7 for each brace, the outer brace-members with the other several parts 10 will be positioned to forcibly bind against the rail along the surface of the ball, the web and the base, while by making the tie rod extend across from rail to rail the pair of rails will be held with reference to each 15 other at the same time that each rail is braced individually in the several directions indicated.

It will further be noted that by reason of this invention the rails will be prevented 20 from spreading one with respect to another, that each rail will be prevented from tipping or overturning, that thereby strains which would tend to lift or pull out the rail spikes will be avoided, all resulting in 25 so securing the rails with respect to each other and with respect to the cross ties as that the perfect gauge of the track will be maintained.

It will further be understood that what 30 is called "tie chewing" will be prevented. This so-called chewing is the action of the car wheels on the upper inner surface of the rail balls, tending to spread the rails and tip them, causing the outer lower flange 35 to dig into the ties and "chew" them. This prevailing objection is overcome by the invention herein described.

Having thus fully described my invention, what I claim as new and desire to 40 secure by Letters Patent is:—

1. In a railway rail brace, the combination with outer braces adapted to fit against the rail ball and inner braces adapted to be urged against other portions of the rail, 45 of a tie rod and nuts adapted to transfer a pressure to the braces, whereby they are made to position firmly against the rail surfaces.

2. In a railway rail brace, the combination with outer braces adapted to engage with the rail ball and inner braces adapted to engage with the rail base, of a tie rod common to both the outer and inner braces and having adjusting nuts by which to press 50 the braces against the rail surfaces.

3. In a railway rail brace, the combination with outer braces whose upper ends are adapted to bear against the rail ball, inner braces adapted to bear on other surfaces of 60 the rail, and a filler block adapted to bear on the rail base, of a tie rod common to the outer and inner braces and the filler block and having nuts thereon by which these several parts are each made to bear

against different portions of the rail by the 65 one adjustment.

4. In a railway rail brace, the combination with a pair of outer braces adapted at one end to bear against the rail ball, and a pair of inner braces adapted to fit between 70 the outer braces and the rail and to bear on parts of the latter, of a tie rod common to both sets of braces and having adjusting nuts which function to cause both sets of braces to bind the rail at their respective 75 points of contact therewith.

5. In a railway rail brace, the combination with a pair of outer braces composed of upper parts and lower parts and a pair of inner braces also composed of upper and 80 lower parts, the upper parts of each outer and inner brace contacting and the lower parts of each outer and inner brace also contacting, of a tie rod common to both sets of braces provided with adjusting nuts 85 which act upon the outer braces and force them and in turn the inner braces against different parts of the rail.

6. In a railway rail brace, the combination with a pair of outer braces and a pair 90 of inner braces, each inner brace and its adjacent outer brace interfitting one another and having a slidable relation, of a tie rod common to both sets of braces provided with adjusting nuts adapted to act on the outer braces to cause them to travel on the inner braces and to cause both sets of braces to bind against portions of the rail.

7. In a railway rail brace, the combination with a pair of outer braces, having 100 grooved inner faces and a pair of inner braces having projecting webs adapted to fit in said grooves, clearance spaces being provided between each and its adjacent outer brace, of a tie rod common to both sets of braces provided with adjusting nuts adapted to act on the outer braces and through 105 them on the inner braces for the purposes set forth.

8. In a railway rail brace, the combination with a pair of outer braces having upper portions to engage the rail ball and provided with lower portions, and inner braces having upper portions located within the upper portions of the outer braces and 115 lower portions located within the lower portions of the outer braces, and a filler block within the inner braces, of a tie rod having adjusting nuts adapted to act on the outer braces and thence on the inner braces and 120 then on the filler block.

9. In a railway rail brace, the combination with an outer pair of braces, an inner pair of braces and a filler block composed of two members, the outer braces having sliding relation with the inner braces and the inner braces sliding relation with the 125 filler blocks, of a tie rod which passes

through the blocks, the inner and the outer braces, and adjusting nuts thereon by which the parts are adjusted and placed in clamping position.

5 10. In combination, a railway rail brace, a filler block having surfaces adapted to engage the edge of the base of a rail, and

another brace adapted to act on such block, and a tie rod adapted to force the last mentioned brace against the block and thereby 10 the block against the rail base.

In testimony whereof, I affix my signature.

JOHN G. MUELLER.
